(57) **CLAIM**

The ornamental design for a combined slider and head for reading or writing information on a disk.

DESCRIPTION

FIG. 1 is a top and left front perspective view of a combined slider and head for reading or writing information on a disk showing our design;

FIG. 2 is a top plan view thereof; and,

FIG. 3 is a rear elevational view thereof.

The portions of the design neither shown in the figures nor described in the specification form no part of the claimed design.

1 Claim, 2 Drawing Sheets

FIG. 1

FIG. 2

FIG. 3
